VARIETAL DENOMINATION

'Pacsam'.

CLASSIFICATION

Pelargonium×hortorum (zonal geranium).

BACKGROUND OF THE INVENTION

The present invention comprises a new and distinct cultivar of zonal geranium known by the varietal name 'Pacsam'. The new variety was discovered in Dresden, Germany as the result of in vitro mutation breeding of the unpatented variety 'PAC Somelia'. The new variety exhibits the dark foliage and branching of its parent, but differs in its growth vigor, flower color and flower size. The new variety was first asexually reproduced by cuttings in Dresden, Germany in 2000. The new variety has been trial and field tested and has been found to retain its distinctive characteristics and remain true to type through successive propagations.
